(57) CLAIM

The ornamental design for a nail polisher as shown and described.

DESCRIPTION

FIG. 1 is a front, left and top perspective view of a nail polisher showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is an enlarged top plan view thereof;

FIG. 8 is an enlarged bottom plan view thereof;

FIG. 9 is an enlarged view of portion 9 shown in FIG. 1; and,

FIG. 10 is an enlarged view of portion 10 shown in FIG. 1.

The evenly-incremented broken lines shown in the drawings illustrate portions of the nail polisher that form no part of the claimed design. The short-dash-long-dash broken lines shown in FIGS. 1, 9 and 10 depict the bounds of the enlarged views as well as the bounds of the portions of the drawings from which they were extracted, and form no part of the claimed design.
